UNITED STATES PATENT OFFICE.

WILLIAM ELIOT BARROWS, OF PHILADELPHIA, PENNSYLVANIA, ASSIGNOR
TO THE WELSBACH LIGHT COMPANY, OF GLOUCESTER CITY, NEW
JERSEY.

DESIGN FOR A GALLERY FOR INCANDESCENT GAS-LIGHTS.

SPECIFICATION forming part of Design No. 25,844, dated July 28, 1896.

Application filed May 14, 1896. Serial No. 591,585. Term of patent 14 years.

To all whom it may concern:

Be it known that I, WILLIAM ELIOT BARROWS, a citizen of the United States, residing at the city of Philadelphia, in the county of Philadelphia and State of Pennsylvania, have invented and produced a new and original Design for Incandescent Gas-Light Galleries, of which the following, taken in connection with the accompanying drawing, is a specification.

The design of my invention relates to Welsbach lights, and more particularly to that part of such lights which is commonly designated the "gallery" and which is usually carried over the shutter and supports the globe or shade and mantle.

The design or invention comprises an ornament or pattern to be wrought or stamped in or otherwise applied to the brass, gold-plate, or other metal or combination of metals which constitutes the gallery. The impression, pattern, ornament, or design is coroniform and is composed of a circle, band, or fillet *a*, having on its lower edge a bead *b* and on its up-

per edge lobe-like projections *c*, alternating with curved dentiform open fretwork terminating in points or projections *d*. The outline of the dentiform projections *d* is curvilinear and acicular, and the openings *e* between the respective frets are also curvilinear in outline, as shown.

The leading feature of my design may be said to be the coroniform gallery, provided on one of its edges with a bead and on the other of its edges with dentiform open fretwork surrounded by acicular or pointed projection *d*, as described.

What I claim as new, and desire to secure by Letters Patent, is—

The design for an incandescent gas-light gallery, substantially as shown.

In testimony whereof I have hereunto signed my name.

WILLIAM ELIOT BARROWS.
